UNITED STATES PATENT OFFICE.

REGNIER EICKWORTH, OF DORTMUND, GERMANY.

OVEN.

Application filed August 24, 1921, Serial No. 494,973, and in Germany December 11, 1913.

(GRANTED UNDER THE PROVISIONS OF THE ACT OF MARCH 3, 1921, 41 STAT. L., 1313.)

My invention relates to annealing ovens, and in particular to ovens of the kind aforesaid in which the objects to be annealed are placed in boxes, each box being supported on a truck and a series of such trucks extending through the oven.

In ovens of this kind as hitherto used, in which the heating gases flow through the oven in a direction opposite to the trucks on which the goods to be annealed are carried and discharged at the discharge end of the oven, the boxes in which the goods are contained are not heated uniformly:

It is an object of my invention to provide means whereby a uniform heating of the boxes and goods is achieved by subdividing the oven chamber into a plurality of chambers arranged in succession. The several chambers are connected by openings which are sufficiently wide to allow the cars to pass through. The gases will successively flow through the several chambers in such a manner that they enter at the bottom of the chambers and are distributed in the chamber, so as to provide uniform heating of the chambers and at the same time a uniform heating of the boxes on the trucks.

The oven is divided into chambers by means of curtains consisting of pieces of fire clay or other refractory material. Such curtains are sufficiently tight for the purpose of the present invention and have the advantage that they are not affected by the temperature existing in the furnace. By means of these curtains the area of the passage between two chambers can be varied as desired.

In the drawings affixed to this specification and forming part thereof, an oven embodying my invention is illustrated diagrammatically by way of example. In the drawings

Fig. 1 is a longitudinal section of the oven.

Figs. 2 and 3 are a partial cross-section and a partial longitudinal section, respectively, drawn to a larger scale and showing one of the partitions or curtains and the means for operating same.

Referring to the drawings, pliable curtains *r* are suspended in the oven *a* by means of which partitions and chambers may be formed as desired. The curtains consist of pieces *s* of fire clay arranged on a thread like string of pearls on the strings of a pearl curtain. The curtains are suspended from rollers *v* by chains and balanced by counterweights *t* on the axle of said rollers. The rollers are arranged in a casing *w*. The curtains are lowered through the ceiling of the oven at such a height that the gases uniformly heat the trucks *g* and boxes *f*. The shafts of the cylinders *v* may be connected so as to turn in synchronism. The oven may also be provided with such a curtain at the entrance and exit.

I wish it to be understood that I do not desire to be limited to the exact details of construction shown and described, for obvious modifications will occur to a person skilled in the art.

I claim:—

1. In an annealing oven a movable partition composed of a plurality of blocks of refractory material connected to form a flexible curtain and rotary means for winding and unwinding such curtain.

2. In an annealing oven a movable partition composed of a plurality of blocks of refractory material connected to form a flexible curtain, rotary means for winding and unwinding such curtain and counterweights arranged to act on said rotary means to compensate the weight of said curtains.

3. An annealing furnace defining a tunnel in which the heating gases flow in longitudinal direction and comprising a truck adapted to move in said tunnel, an annealing box on said truck and partitions arranged in said tunnel in spaced relation and comprising a plurality of blocks of refractory material which are so connected to each other as to permit said blocks to adjust themselves with regard to each other, said partitions being adapted to be raised and lowered with regard to said truck so as to close said tunnel in cooperation with said truck, excepting a passage at the base of the tunnel.

4. An annealing furnace defining a tunnel in which the heating gases flow in longitudinal direction and comprising a truck adapted to move in said tunnel, an annealing box on said truck, curtains arranged in said tunnel in spaced relation and comprising a plurality of blocks of refractory mate-

rial in close vicinity and so connected as to move independently with regard to each other, and means for raising and lowering 10 said curtains.

In testimony whereof I affix my signature.

REGNIER EICKWORTH.
